BOBBIN

Hans Summa, Schwarzenbach-on-the-Saale,
GermanyApplication March 7, 1932, Serial No. 597,337
In Germany March 12, 1931

2 Claims. (Cl. 139—207)

My invention relates to bobbins for shuttles, and more particularly to means for connecting the purn and the peg.

It is an object of my invention to provide a connection which reliably holds the purn on the peg even if the shuttle is moved rapidly during its operation but does not require an effort for setting it.

It is another object of my invention to so design the connection that it will not cause deformation of the peg or the purn.

It is still another object of my invention to so design the connection that it will not increase the over-all length of the peg and the purn, and center the purn on the peg.

It is still another object of my invention to so design the connection that the amount of material required for it is small and the extra weight and the increase of inertia it brings about are negligible.

It is still another object of my invention to so arrange the connection that it will not exert any mechanical or chemical influence on the thread on the purn so that breaking of the threads for these causes is eliminated.

It is still another object of my invention to so design the connection that it may be fitted to existing pegs and purns, so that the same bobbins may be used for spinning and for weaving factories.

With these objects in mind, I provide a sleeve in the purn and means for connecting the sleeve to the peg.

In a preferred embodiment of my invention, I provide a bayonet joint for connecting the purn to the peg, the sleeve having a slot or a pair of slots and being arranged at the big end of the purn while the pin, or pins, of the joint are arranged in a corresponding position on the peg.

In the accompanying drawings, several embodiments of my invention are illustrated by way of example.

In the drawings

Figs. 1 to 4 illustrate a purn having a plain sleeve with a bayonet slot,

Fig. 1 is an elevation of the peg,

Fig. 2 is an elevation of the purn,

Fig. 3 is an axial section of the purn, and

Fig. 4 shows the purn in section placed on the peg.

Figs. 5 and 6 illustrate a purn having a threaded sleeve with a bayonet joint,

Fig. 5 is a partly sectional elevation of the purn, and

Fig. 6 is an end elevation of the sleeve, viewed from the big end of the purn.

Fig. 7 is an axial section of an existing purn having means for securing the sleeve in Figs. 5 and 6 to it.

Figs. 8 to 11 illustrate a purn having a flanged sleeve with camways for the bayonet-joint pins,

Fig. 8 is partly an elevation and partly an axial section of the purn and the sleeve,

Fig. 9 is an elevation of the sleeve,

Fig. 10 is an end elevation of the sleeve, partly in section on the line X—X in Fig. 9, and

Fig. 11 is a section on the line XI—XI in Fig. 10.

Referring now to the drawings, and first to Figs. 1 to 4, 1 is a peg, here shown as a double spring peg or Northrop skewer by way of example. 2 is its butt, and 3 is the purn. The peg and purn may be of any suitable and normal size and shape and the purn may be of layers of paper, cardboard or the like. 4 is a sleeve which is inserted in the big end of the purn 3; 5, 5 are its bayonet slots, each with a seat 6 at its upper end, and 7 are the bayonet pins on the peg.

The sleeve 4 is preferably made of a stronger material than the purn 3, for instance, of metal. This has the advantage that the slots 5 will not become deformed and worn even if used for a long time and the connection remains reliable.

By arranging the sleeve 4 in the purn 3, the perimeter of the purn remains quite smooth so that the threads have no tendency to break, and chemical reactions of the thread with the sleeve are prevented. The sleeve in the purn is smaller than would be a sleeve on the purn, and of lighter weight. Furthermore, it is much easier to secure the sleeve in the purn than on it. This is important for quantity production. The inertia of the sleeve is reduced which is particularly favorable if the purn is used for spinning.

Preferably the inside diameter of the sleeve 4 is made a little larger than the outside diameter of the corresponding portion of the peg 1 so that the peg is free to yield to centrifugal and other forces and behaves like a flexible shaft. Irregularities in the size of the peg are also made up for by the clearance thus provided and seizing of the sleeve on the peg is prevented as only the material of the purn, such as cardboard etc., and not the metal sleeve, engages the peg.

The two pins 7 which are normally radial, are also easily assembled without any appreciable cost.

The peg is preferably made longer than the purn, as best seen in Fig. 4. This not only protects the small end of the purn but also centers

the pirn on the peg. The centering is important as it facilitates the engagement of the pins 7 with the slots 5. It is to be observed that the radial extension of the pins 7 is such that their outer ends clear the inner wall of the pirn when the latter is moved to engage the pins with the angular slots 5.

Referring now to Figs. 5 and 6, the sleeve 41 is serrated or threaded on its perimeter and 10 the serrations or threads are preferably of the buttress type so as to form a sort of hook pointing to the big end of the pirn 31. This is important as it holds the sleeve against axial displacement on the pirn which might occur when 15 the pirn is pulled off the peg.

The firm hold the threaded or serrated sleeve 41 has in the pirn, may be further improved by applying an adhesive to the threaded or serrated portion of the sleeve. Longitudinal 20 grooves 9, Fig. 6, are formed in the threaded or serrated portion. The grooves which may be of V section as shown, or of any other section, may be arranged at diametrically opposite sides of the sleeve but obviously any number and arrangement of grooves may be provided. The adhesive 25 is introduced through the grooves and distributed over the serrations or threads of the sleeve 41.

Referring now to Fig. 7, this shows the adaptation of the sleeve 41 to an existing pirn 32. 30 10 is a fitting which may be of wood or any other suitable material and is inserted in the pirn 32. It has an axial tapered bore to fit the peg and at its big end is equipped with the threaded or 35 serrated sleeve 41 as shown in Fig. 5. By these means, the same pirns may be used for spinning and weaving which is very desirable with respect to standardization.

Obviously the fitting of a sleeve to an existing 40 pirn is not limited to serrated or threaded sleeves.

A sleeve of particular design is illustrated in Figs. 8 to 11. The sleeve 4 has flanges 11 and 45 12 at opposite ends. Its shell is slightly tapered and has camways pressed into it for the reception of the pins 7 on the peg. In the example illustrated, two camways 14 are arranged at diametrically opposite sides of the sleeve. The cam-

ways are so deep that their outer walls are flush with the flanges 11 and 12. Each camway 14 has a flared inlet 15 and a parallel seating portion 16 in which the pins 7 engage in the final position of the pirn on the peg. There may be any 5 number of camways, each with a flared inlet for facilitating the introduction of the pins 7.

The flanges 11 and 12 of the sleeve 43 form a flat and wide channel for the reception of one or more strips of paper or the like 17. The winding of the strip is facilitated by the flushness of the outer walls of the camways 14 with the flanges 11, 12. Pasted on the strip 17 in the channel is a hollow body 18 which also may be wound from one or more strips of paper or the like. 15 The body 18 receives the pirn 33. It may be pasted to the pirn or may be integral with it. The sleeve 43 in this manner is inserted quite firmly in the body of the pirn without any coercion. If desired, the strip or strips 17 may 20 be pasted on the sleeve 43 between its flanges but this is not necessary.

Preferably the bayonet joint is so arranged that it is set by turning to the left, as shown, so that it will not work loose in the operation of 25 the loom during which the pirn has a tendency to turn toward the left.

I claim:

1. A bobbin for shuttles comprising a fixed peg and a pirn adapted to be placed on said peg, 30 a metal sleeve rigidly secured to the inside of said pirn at the base thereof, so as to be totally enclosed within said pirn, a thread of the buttress type on said sleeve for holding it against axial displacement in said pirn, and a bayonet joint 35 also enclosed within said pirn for detachably connecting said peg and said sleeve.

2. A bobbin for shuttles comprising a fixed peg and a pirn adapted to be placed on said peg, a metal sleeve rigidly secured to the inside 40 of said pirn at the base thereof, so as to be totally enclosed within said pirn, said sleeve having grooves for admitting adhesive between said sleeve and said pirn, and a bayonet joint also enclosed within said pirn for detachably connecting 45 said peg and said sleeve.

HANS SUMMA.
